UNITED STATES PATENT OFFICE.

GEORGE W. COPE AND WILLIAM L. BERTRAM, OF DETROIT, MICHIGAN, ASSIGNEES TO
ECONOMY STOVE COMPANY, OF CLEVELAND, OHIO, A PARTNERSHIP.

DESIGN FOR A STOVE.

40,271.

Specification for Design. Patented Sept. 21, 1909.

Application filed July 6, 1909. Serial No. 506,256. Term of patent 14 years.

To all whom it may concern:

Be it known that we, GEORGE W. COPE and WILLIAM L. BERTRAM, citizens of the United States, residing at Detroit, in the county of Wayne and State of Michigan, have jointly invented a new, original, and ornamental Design for Stoves, of which the following is a specification, reference being had to the accompanying drawings, forming part hereof.

Figure 1 is a front plan view of the stove

showing our new design, and Fig. 2 is a side elevation of said stove showing our new design.

We claim:

The ornamental design for a stove, as shown.

GEORGE W. COPE.
WILLIAM L. BERTRAM.

Witnesses:

W. J. BELKNAP,
JAMES P. BARRY.
